UNITED STATES PATENT OFFICE.

EDWARD TILSTON, OF LONDON, ENGLAND.

INTERNAL-COMBUSTION ENGINE.

1,234,825.

Specification of Letters Patent. Patented July 31, 1917.

Application filed August 16, 1916. Serial No. 115,224.

To all whom it may concern:

Be it known that I, EDWARD TILSTON, a subject of the King of Great Britain, residing at London, England, have invented certain new and useful Improvements in Internal-Combustion Engines, of which the following is a specification.

This invention relates to improvements in that class of four-stroke cycle internal combustion engines in which the cylinder is provided with inlet and exhaust ports at its ends controlled by a valve reciprocating in a valve chest at the side of the cylinder the inlet port also being controlled by the engine piston.

According to this invention an engine of this type is adapted to compress air in the crank case and is provided with a scavenger port at the same end of the cylinder as the inlet port, the arrangement being such that during induction the inlet port and scavenging port are uncovered and a combustible charge is admitted to the cylinder, whereas at the end of the firing or explosion stroke the inlet port is covered by the valve and the scavenging port is alone effective, to admit air from the crank case for scavenging and cooling purposes.

In the drawings:

Figure 1 is a sectional elevation of a four-stroke cycle engine according to the invention, and

Figs. 2 and 3 cross sections of the valve chest and cylinder on the lines 2-2, 3-3, Fig. 1.

Fig. 4 is a diagrammatic plan showing the arrangement of four cylinders.

In carrying out the invention in the application to a four-cycle engine as illustrated by Figs. 1 to 3, the cylinder *a* is provided with an exhaust port or set of ports *b* in its side at the upper end above the extreme upper position occupied by the piston *c*. It has a second port or set of ports *d* in its lower part in a position where they are uncovered by the piston *c* as it reaches its lowermost position. The second set of ports *d* form the inlet which is thus controlled by the piston *c*. On the opposite side of the cylinder is a third set of ports *e* also controlled by the piston *c* and adapted to be uncovered when the piston *c* is in its lowermost position. The third set of ports communicate with the crank chamber *f*, for example the cylinder *a* has an extension *a'* which passes into an upper extension *g* on

the crank chamber *f* so that an annular space *h* exists between it and this extension *g*, forming a passage for scavenging air from the crank chamber *f* to the third set of ports *e*.

At the side of the cylinder *a* and preferably in the same casting therewith is a tubular valve chest *i* in which a piston valve *k* slides. The upper part of the chest forms the exhaust passage into which the exhaust ports lead and the interpenetration of the cylindrical chest *i* and the upper part of the engine cylinder *a* enable large exhaust ports *b* to be provided as is clearly shown in Fig. 2. The upper end of the chest *i* may be closed by a screwed plug *l* and a branch *m* may be provided for connection to an exhaust pipe, whereas in engines for aeroplanes the plug *l* may be omitted and the end of the chest may be left open, and the chest need not project so far beyond the head of the cylinder.

The piston valve *k* preferably comprises a hollow cylinder the diameter of which is about half that of the engine cylinder. At the lower end it is fitted with an extension *o* which comprises a narrow central neck *p* and a short cylindrical portion *q* forming a piston.

In the outer wall of the valve chest two ports or sets of ports are formed one an inlet port *r* from the carburetor and the other an air inlet *s* for the crank chamber. The upper port *r* namely the fuel inlet, is controlled by the piston valve *k* while the lower port *s* namely the air inlet for the crank chamber *f*, is controlled by the short piston or extension *q* on the piston valve. The admission of air to the crank case may be effected by an automatic or mechanically operated check valve in known manner, if desired.

The piston valve *k* and its extension *q* are reciprocated by a crank disk *t* and connecting rod *u* from a half time shaft *v* driven off the engine shaft *z* by a train of gearing *w, x, v*. The shaft *v* is preferably centrally below the axis of the piston valve *k* so that the angle through which the crank pin passes in the lowermost part of its path is equally divided by the center line, and this part corresponds with the opening of the exhaust ports. As the pin is at the lower part of its path the opening of the exhaust ports is long, that is to say it has a long dwell, as the valve travels slowly while

the pin is passing over this part of its path. In Fig. 1 the path of the crank pin is shown divided into four parts I, II, III, and IV, over which the pin is passing during the 5 periods of "inlet," "compression," "explosion" and "exhaust," respectively.

The cycle of operations is as follows:—

Assuming the piston *c* has just reached the top of the exhaust stroke, the piston 10 valve *k* will be traveling upward and have just closed the exhaust port *b*. The piston *c* will then descend and a partial vacuum will occur in the cylinder *a* above the piston *c*. When the piston *c* nears the end of 15 its downward stroke the inlet ports *d* will be uncovered by it. Consequently a charge of carbureted air will enter the cylinder *a* and fill it. On the next upstroke of the piston *c* this charge will be compressed, as the 20 exhaust ports *b* will still be covered by the piston valve *k*. When the piston *c* completes its compression stroke, ignition occurs and the piston descends. In due time the piston valve *k* also descending, uncovers the 25 exhaust ports *b* in the cylinder and closes the inlet port *r* to the valve chest *i* and the inlet ports *d* in the cylinder. Consequently, as the piston *c* reaches the end of the 30 explosion stroke the scavenging ports *e* only are effective at the lower end of the cylinder, and the air, admitted to the crank chamber *f* by the air inlet port *s* controlled by the extension piston *q* on the piston valve *k*; and compressed in the crank chamber *f* by the descent of the piston *c*, enters at the 35 lower end of the cylinder and scavenges the cylinder *a* from that end upward to the exhaust ports *b* at the top. The piston *c* then ascends and completes the expulsion of 40 burnt gases from the cylinder and the cycle is repeated.

When a number of cylinders *a* are arranged on the same crank shaft as indicated in Fig. 4, the crank case *f* is divided by 45 partitions *g* into separate compartments, one for each cylinder.

I claim:—

1. An internal combustion engine comprising a crank case, a cylinder, a piston 50 reciprocating therein, and a valve chest adjacent to said cylinder, said cylinder having an exhaust port at one end in a position beyond the limit of each inward stroke of said piston and communicating with said valve 55 chest; and an inlet port at the other end adapted to be uncovered by the piston as

it nears the limit of each outward stroke, said inlet port also communicating with said valve chest, a reciprocating valve in said valve chest for opening and closing 60 said exhaust port and said inlet port, the said cylinder having a scavenging port at the same end as said inlet port and also adapted to be uncovered by the said piston at the end of its outward stroke, said 65 scavenging port communicating with the crank case, means for admitting carbureted air to said valve chest in a position close to said inlet port, means for admitting air to said crank case; and means for reciprocating said valve in synchronism with the said piston whereby at the end of the induction stroke of said piston the said inlet and scavenging port are open for the purpose of admitting carbureted air and air to the cylinder, whereas at the end of the firing stroke the said inlet port is closed by the said valve but the scavenging port is open for the purpose of admitting air for scavenging and cooling purposes, substantially as herein- 70 before set forth.

2. An internal combustion engine comprising a cylinder, a piston reciprocating therein, a valve chest adjacent to said cylinder, a piston-valve in said chest, said cylinder having an exhaust port at one end in a position beyond the limit of each inward stroke of said piston and communicating with said valve chest, and an inlet port at the other end adapted to be uncovered by 75 said piston as it nears the limit of its outward stroke, a crank case having an air inlet port, an extension on the aforesaid piston-valve for opening and closing said port, the aforesaid cylinder further having a 80 scavenging port communicating with said crank case and adapted to be uncovered by the aforesaid piston at the end of its outward stroke, and coöperating cranks connected to said piston and the extension of 85 said piston-valve, said cranks being central in relation to the piston and extension respectively, substantially as and for the purpose hereinbefore set forth.

In testimony whereof I have signed my 90 name to this specification in the presence of 100 two subscribing witnesses.

EDWARD TILSTON.
